UNITED STATES PATENT OFFICE.

WALTER MENELIOUS SURFACE, OF KINGMAN, KANSAS.

OIL-BURNER.

1,106,426.

Specification of Letters Patent. Patented Aug. 11, 1914.

Application filed April 15, 1914. Serial No. 832,030.

To all whom it may concern:

Be it known that I, WALTER M. SURFACE, a citizen of the United States, residing at Kingman, in the county of Kingman and State of Kansas, have invented a new and useful Oil-Burner, of which the following is a specification.

The present invention appertains to oil or hydro-carbon burners, and aims to provide 10 a novel and improved device of that character.

The present invention contemplates the provision of a hydro-carbon burner of unique construction, which will possess two 15 atomizing means, for thoroughly atomizing the fuel, by means of steam or other pressure fluid, and whereby the combustion of the mixture will be of a high order.

Another object of the present invention is 20 to provide a hydro-carbon burner wherein means is provided for controlling the flame, whereby the length of the flame may be varied as well as the width of the flame, and whereby the flame may be directed in various 25 directions, as desired. It is also within the scope of the present invention to provide in an appliance of the present character, such a combination and assemblage of the component parts, as to enhance the utility of the 30 burner.

With the foregoing general objects outlined, and with other objects in view, which will be apparent as the nature of the invention is better understood the invention re- 35 sides in the combination and arrangement of parts and in the details of construction hereinafter described and claimed, it being understood that changes in the precise embodiment of the invention herein disclosed, can 40 be made within the scope of what is claimed, without departing from the spirit of the invention.

The invention has been illustrated in its preferred embodiment in the accompanying 45 drawing, wherein:

Figure 1 is a side elevation of the improved burner, portions being broken away, and portions being shown in section. Fig. 2 is a horizontal section of the burner, por- 50 tions being shown in full. Fig. 3 is a lateral or cross section of the burner, taken on the line 3—3 of Fig. 2.

In carrying out the present invention, there is provided a hollow body 1, preferably 55 tubular or cylindrical, and preferably, although not necessarily, of sectional construc-

tion. As illustrated, the body 1 comprises a rear section 2 and an intermediate section 3, which are connected by means of an inner coupling or sleeve 4 threaded into the adja- 60 cent ends of the sections 2 and 3. The body 1 further includes a forward section 5 threadedly or otherwise engaged to the forward end of the intermediate section 3, and providing with the intermediate section, a 65 mixing chamber 6.

The forward or outer end of the body 1, or the forward section 5 thereof, is provided with a reduced outlet 7, preferably in the form of a nozzle or nipple, and a hollow 70 burner head 8 is threadedly or otherwise engaged over the outer or free end of the nozzle or nipple 7. The burner head 8 is preferably circular in plan, and has its back wall engaged to the nipple or nozzle 7, the top 75 and bottom 9—9 of the burner head 8 being preferably removable. The front wall of the burner head 8 is provided with an arcuate slot 10 lying in the horizontal plane in which the axis of the body 1 and nipple or nozzle 7 80 lies. The head 8 provides a secondary mixing chamber which communicates with the primary mixing chamber 6, and from which the final mixture is adapted to pass to support combustion, as will hereinafter more 85 fully appear.

Threaded or otherwise engaged into the rear or inner end of the body 1, or the rear section 2 thereof, is a plug or annulus 11 having a central opening 12, which cooperates with a partition or diaphragm 13 formed within the collar 4, to provide a steam chamber 14 within the rear section 2. The partition or diaphragm 13 is provided with apertures or openings 13a adjacent the 95 rim or collar 4, and is provided with a central threaded opening through which is threaded the forward end of an oil tube or pipe 15 passed through the opening 12 of the ring or annulus 11. The oil tube or pipe 100 15 thus passes axially through the steam chamber 14, and preferably has a nozzle or nipple 16 threaded or otherwise engaged within its forward end, to serve as a constricted outlet for the oil or fuel. A jam or 105 binding nut 17 is threaded upon the rear end portion of the tube or pipe 15 and bears against the rear face of the ring or closure 11, to close the opening 12 in the ring or annulus 11, should the tube or pipe 15 fit 110 loosely within the said opening, the nut 17 also locking the tube or pipe 15 in place.

A controlling valve 18 is connected to the rear end of the fuel tube or pipe 15, and has attached to the lower end thereof, a liquid fuel supply pipe 19 leading to any suitable source of fuel, whereby the fuel may be fed by gravity, or under pressure, which ever is desired. The valve 18 thus serves as a coupling for connecting the liquid fuel supply pipe 19 and the discharge tube or pipe 15, and also serves to control the flow of liquid fuel into the tube or pipe 15.

Steam or other pressure fluid is supplied into the steam chamber 14, by means of a pipe section 20 threadedly or otherwise engaged through the top or crest of the rear section 2 of the body 1, and having a valve 21 engaged thereon for controlling the flow of steam or pressure fluid into the chamber 14. A coupling 22 is attached to the upper end of the valve 21, for the connection of the steam supply pipe 23.

In order to supply steam or pressure fluid to the burner head or secondary mixing chamber 8, depending pipes 24 having their upper ends connected to the opposite sides of the coupling 22 above the controlling valve 21, and have valves 25 attached to their lower ends. Horizontal or longitudinal pipes 26 have their rear ends connected to the valves 25, the said valves serving as couplings between the pipes 24 and 26, and the forward ends of the pipes 26 are threadedly or otherwise engaged through the rear portion or wall of the head or case 8 adjacent the nipple or nozzle 7. The forward end portions 27 of the pipes 26 converge at the sides of the nipple or nozzle 7, and are directed to the center of the head 8, in advance of the nipple or nozzle 7. The forward end portions 27 of the pipes 26 serve as nozzles for the discharge of steam into the burner head 8 to provide a secondary atomization of the fuel, as will hereinafter more fully appear. The pipes 26 have interposed therein, couplings 28, which enable the sections of the pipes 26 to be readily detached and attached for the purpose of separating or assembling the structure.

From the foregoing, taken in connection with the drawing, it will be obvious that the present apparatus may be readily assembled, and applied to a steam boiler, stove, or other structure to be heated.

In operation, supposing the auxiliary steam valves 25 to be closed, and supposing the main steam valve 21 to be open, it will be obvious that the steam will be admitted from the steam supply pipe 23 into the steam chamber 14, so as to be discharged through the apertures or outlets 13^a in the partition 13 at the forward end of the steam chamber 14, into the mixing chamber 6. The streams of steam or pressure fluid issuing from the apertures 13^a will pass over the sides and free end of the nozzle or nipple 16 of the

fuel pipe 15 thereby tending to create a vacuum in advance of the nozzle or tip 16, whereby when the oil valve 18 is opened, to admit oil into the pipe 15, the oil or other fuel will be sucked into the mixing chamber 6, so as to commingle with the steam, and become atomized or vaporized. The fuel pipe 15 being disposed within the steam chamber 14, will become heated by the steam, so as to give an initial heat to the fuel, prior to the atomization or vaporization of the fuel within the mixing chamber 6. The pressure of the steam will force the mixture from the chamber 6 through the nozzle or nipple 7 into the burner head 8, and thence through the slot or discharge opening 10 to support combustion, the flame being ignited in any suitable manner.

When the valves 25 are closed, as above indicated, the combustible mixture issuing from the nozzle or nipple 7 from the mixing chamber 6, will be thrown forwardly or outwardly with considerable force, so as to provide a relatively long flame. Now, to provide a secondary atomizing action of the fuel, the valves 25 are opened, which will admit steam from the supply pipe 23 into the steam pipes 26, the steam being discharged into the burner head 8 through the nozzles 27 of the pipes 26. The converging streams of steam issuing from the nozzles 27, will intercept the stream of the mixture issuing from the nozzle or nipple 7 from the mixing chamber 6, and as a consequence, a second atomizing action will take place within the burner head 8, tending to more thoroughly atomize the fuel consisting of a mixture of steam and oil passing through the nozzle or nipple 7 into the burner head 8. In this manner, a double atomizing function is accomplished by the present burner, in order that the final mixture passing through the outlet 10 of the burner head 8, will be thoroughly combustible, to attain a maximum heating effect with a minimum amount of fuel, and with a minimum amount of soot.

The auxiliary supply of live steam into the burner head 8 from the converging nozzles 27, is employed as an important factor for controlling the flame or flames. Thus, by properly controlling the opposite valves 25, so as to vary the streams of steam issuing from the opposite nozzles 27, the pressure of the two auxiliary streams of steam may be varied or regulated, for controlling the flame. When the auxiliary streams of steam are of equal pressure, the flame will be directed longitudinally, and will be spread laterally more or less, according to the pressure of the auxiliary streams of steam. Thus, when the auxiliary streams of steam have little pressure, they will not spread the flame to any appreciable extent, and will not decrease the length of the flame materially. However, when the auxiliary streams of

steam are of considerable force, they will not only serve to atomize the fuel in a thorough manner, but they will cause the flame to be spread in a fan-shape manner, in order that the flame will cover a greater area.

Another salient or cardinal feature resides in the fact that when the auxiliary streams of steam issuing from the nozzles 27, are of different pressures, the flame will be thrown to one or the other side, as will be obvious. This result is accentuated when one of the valves 25 is closed, while the other is opened more or less, so as to direct the flame toward the other side. It is thus an easy matter for the operator or attendant to control the flame to suit the conditions desired, the valve 18 controlling the intensity of the flame, by regulating the flow of the fuel, which may be of any character, such as crude oil, refined oil or the like. The size and shape of the flame may be controlled to a nicety, by properly manipulating the valves 21 and 25, as will be apparent from the foregoing.

The other advantages and capabilities of the present invention will be obvious to those versed in the art, without further comment being necessary.

Having thus described the invention, what is claimed as new is:—

1. In a hydro-carbon burner, communicating primary and secondary mixing chambers, a pressure fluid chamber communicating with the primary mixing chamber, fuel supplying means communicating with the primary mixing chamber, valve-con-

trolled pressure fluid supplying means communicating with the pressure fluid chamber, and a pair of valve-controlled pressure fluid supplying means including converging nozzles attached to the secondary mixing chamber, said secondary mixing chamber having an outlet.

2. In a hydro-carbon burner, a primary mixing chamber having a nipple at one end, a secondary mixing chamber attached to the said nipple and having an opposite outlet, coöperating fuel supplying means and pressure fluid supplying means communicating with the primary mixing chamber, and a pair of pressure fluid supplying means including controlling valves, and converging outlet nozzles attached to the secondary mixing chamber at the opposite sides of the said nipple.

3. In a hydro-carbon burner, a primary mixing chamber having an outlet nipple, a secondary mixing chamber attached to the said nipple and having an opposite outlet, and a pair of valve-controlled pressure fluid supplying means having converging outlet portions connected to the secondary mixing chamber adjacent the said nipple.

In testimony that I claim the foregoing as my own, I have hereto affixed my signature in the presence of two witnesses.

WALTER MENELIUS X SURFACE.
